UNITED STATES PATENT OFFICE.

LEROY F. BOOMER, OF CLEVELAND, OHIO.

DESIGN FOR A HEMMED FABRIC.

SPECIFICATION forming part of Design No. 30,126, dated January 31, 1899.

Application filed November 11, 1898. Serial No. 696,182. Term of patent 3½ years.

To all whom it may concern:

Be it known that I, LEROY F. BOOMER, a citizen of the United States, residing at Cleveland, in the county of Cuyahoga and State of Ohio, have invented and produced a new and original Design for a Hemmed Fabric, of which the following is a specification, reference being had to the accompanying drawings, forming a part thereof.

10 The fabric which constitutes my design has a hem which produces a peculiarly ornamental and pleasing appearance.

The drawings clearly illustrate my fabric, wherein—

15 Figure 1 is a view of its face or front side; Fig. 2, a back view, and Fig. 3 a perspective view showing the end edge.

As shown in the drawings, the leading or material features of my design consist of a 20 fabric having a bead formed on the front side some distance back from the edge and a fold caused by bending the fabric between the bead and the edge over onto the back side of the fabric and securing the extreme edge 25 within the bead. Thus the extreme edge of the fabric at the hemmed side is invisible from either the front or back, while the bead gives the fabric a very pleasing appearance.

Referring to the parts by letters, A repre-

sents the fabric as a whole; a, the bead; a', the 30 front side of the fold; a², the back side of the fold, and a³ the extreme edge, which is contained within the bead. Stitches B' B² extend along each side of the bead through the fabric, the stitches B' passing also through 35 the fold a² on the rear side. A thread B³ zig-zags across the entrance to the bead on the back side of the fabric and receives the loops of the two threads B' and B², whereby the appearance is as shown in the drawings—that 40 is, an ordinary stitch on each side of the bead on the front side of the fabric and a zigzag stitch on the back side of the fabric across the entrance to the bead. In practice these stitches are made with a machine having two 45 needles and one shuttle.

Having described my invention, what I claim as new, and desire to secure by Letters Patent, is—

The design for a hemmed fabric substantially as herein shown and described.

In testimony whereof I hereunto affix my signature in the presence of two witnesses.

LEROY F. BOOMER.
